UNITED STATES PATENT OFFICE.

ARNOLD A. SCHAEFFER, OF HOUSTON, TEXAS.

DOOR LATCH.

Application filed May 1, 1926. Serial No. 106,131.

This invention relates to door latches of the sliding bolt type, and has for one of its objects to provide a novel device of this character which shall be especially adapted 5 for use on barn and crib doors and embodying means adapted to prevent the retraction of its bolt by horses or other cattle and by persons not familiar with its mechanism.

With the foregoing and other objects in 10 view, the invention consists of the novel construction, combination and arrangement of parts hereinafter fully described and claimed, and illustrated in the accompanying drawing, wherein:

Figure 1 is an elevational view illustrating the application of the door latch,

Figure 2 is a detail view in rear elevation of the door latch,

Figure 3 is a sectional view taken on the 20 vertical plane indicated by the line 3—3 of Figure 1,

Figure 4 is a sectional view taken on the vertical plane indicated by the line 4—4 of Figure 1, and

Figure 5 is a similar view taken on the 25 horizontal plane indicated by the line 5—5 of Figure 1.

Corresponding and like parts are referred to in the following description, and designated in the several views of the accompanying drawing, by similar reference characters.

The latch comprises a casing 1 which, as shown in the drawing, is adapted to be secured to a door 2 by bolts 3, and a keeper 4 which is adapted to be secured to the frame 5 of the door by bolts 6. The casing 1 is provided with a horizontal opening 7 in which is slidably mounted a bolt 8, and the keeper 4 is provided with a recess 9 for the 40 reception of the forward end of the bolt. The rearward end of the bolt 8 projects beyond the casing 1, and is provided with a knob or handle 10 through the medium of which the bolt may be readily projected or 45 retracted. A pin 11 carried by the bolt 8 and working in a closed end groove 12 in the casing 1, prevents the bolt from being casually withdrawn from the casing and limits the distance that the bolt may be 50 moved during the act of projecting it or moving it into engagement with the keeper 4. The bolt is adapted to be secured in projected position by tumblers 13 and 14 which are slidably mounted in vertical openings 55 formed in the casing 1. The openings 15 intersect the opening 7 and extend through

the bottom of the casing 1. The tumbler 13 is adapted to enter a notch 16 in the upper edge of the bolt 8, and is provided with a stem 17 extending downwardly therefrom and having its lower end positioned within the plane of the casing 1. The tumbler 14 is adapted to engage in a notch 18 in the upper edge of the bolt 8, and is provided with a stem 19 extending downwardly therefrom and having its lower end projecting below the corresponding end of the casing 1. The tumbler 14 is provided with a notch 20 which receives the bolt 8 and is longer than the width of the bolt. A notch 21 is formed 60 in the lower edge of the bolt 8 for the reception of the tumbler 14 in the event that the tumbler should be lifted too high when manipulating the tumblers to release the bolt.

In practice, the tumblers 13 and 14 rest upon the upper edge of the bolt 8 when the latter is in retracted position. The pin 11 limits the distance that the bolt 8 may be moved, and when the latter reaches the 70 limit of its projected position the notches 16 or 18 will register with the tumblers 13 and 14 and the tumblers will gravitate into the notches and lock the bolt against retraction by an animal or person unfamiliar with the 75 manner in which the tumblers must be manipulated in order to release the bolt. The tumblers 13 and 14 may be raised into bolt releasing position by engaging the lower end of the stem 17 with a key, which 80 may take the form of a pin, and the lower end of the stem 19 with the finger. If the tumbler 14 is raised too high it will engage in the notch 21 in the lower edge of the 85 bolt 8.

From the foregoing and accompanying drawing, it will be apparent that the bolt 8 will immediately on reaching its fully projected position be positively locked in such 90 position, that a person not familiar with the mechanism of the latch cannot effect the quick release of the bolt 8, and that the latch is simple and durable and may be manufactured and sold at a comparatively low cost.

It should be understood that the drawing 100 is merely illustrative and does not pretend to give exact proportions. Furthermore, the said drawing is illustrative of a preferred construction, it being my expectation that various changes and modifications may 105 be made without departing from the spirit and scope of my invention.

What is claimed is:—

1. A latch comprising a casing, a bolt slidably supported by the casing and provided in its upper and lower edges with 5 notches, a key operated tumbler, and a manually operable tumbler, said tumblers being adapted to engage in the notches in the upper edge of the bolt to secure the latter in projected position, and the manually operable tumbler being adapted to engage in the notch in the lower edge of the bolt provided said tumbler is moved through 10 too great a distance during the operation thereof to effect the release of the bolt.
15. 2. A latch comprising a casing, a bolt

slidably supported by the casing and provided in its upper edge with a plurality of notches and in its lower edge with a single notch, a key operated tumbler adapted to engage in one of the notches in the upper 20 edge of the bolt and located wholly within the casing, and a manually operable tumbler adapted to engage in the other notch in the upper edge of the bolt and adapted to be engaged in the notch in the lower edge of 25 the bolt provided it is moved through too great a distance during its manipulation to release the bolt.

In testimony whereof I affix my signature.

ARNOLD A. SCHAEFFER.
